UNITED STATES PATENT OFFICE

ANNA N. JAMES, OF PROTEM, MISSOURI

QUILTING FRAME

Application filed May 7, 1932. Serial No. 609,863.

This invention relates to quilting frames and more particularly to such frames of the knockdown type; and in accordance with the present invention the frame will be found useful for a number of other purposes the making of rugs, embroidering and the like.

The invention together with its numerous objects and advantages will be best understood from a study of the following description, taken in connection with the accompanying drawings wherein:

Figure 1 is a perspective view of the frame.

Figure 2 is a transverse sectional elevation view therethrough.

Figure 3 is a sectional view through one end of a side member or quilt carrying roll forming part of the work frame.

In the preferred embodiment of the invention there is provided a supporting structure which comprises a pair of uprights 5 provided with legs 6.

A work frame comprises a pair of end members 7 provided adjacent each end with bayonet slots 8; and quilt carrying rollers or side members 9 supported between and connecting the end members 7.

Each frame member 9 is preferably rectangular or non-circular in cross section, and at each end is reduced as at 9a. A sleeve 10 is secured to each reduced end 9a by pins or the like 11. Each sleeve 10 has a free end that is contracted and integral with the contracted end is a ratchet wheel 12. When the work frame is assembled the reduced end 10a of the sleeve fits into the slot 8 as suggested in Figure 2.

Each frame member 7 is provided adjacent each slot 8 with a pivoted pawl 13 to engage a proximate ratchet 12 as shown in Figure 1.

The uprights 5 are provided with vertical sockets 14 elongated longitudinally; and the end members 7 are provided with depending adjusting bars 15 slidably engaging the sockets 14. The bars 15 are provided with vertically spaced apertures 16 and pins 17 are adapted to engage selected apertures 16 at the upper ends of the uprights 7 whereby to secure the adjusting bars 15 at the desired vertical adjustment.

Each adjusting bar 15 is braced relative to its frame bar 7 through the medium of a pair of brace rods 18 the ends of which connected with the bar 15 operate in oppositely disposed slots 19 provided in the upright 5. 55

Each frame member 7 on its inner side has tacked or otherwise secured thereto as at 20 one edge portion of a fabric sheet 21 to which may be pinned the ends of a quilt or the like. The sheets 21 are of some strong fabric such as canvas.

As is thought well known, in actual practice, the quilt is secured in any suitable manner to one of the rolls or side members 9 and is rolled about the other of the rollers or side members for holding the material or quilt stretched between the rollers or side members 9, and the pawls 13 engaging the ratchet wheels 12 retain the rollers or frame members 9 against retrograde movement. Manifestly, the quilt being also pinned to the sheets 21 will be stretched and held taut in a direction transversely of the stretching action of the rollers or side frame members 9. 75

It will also be apparent that the work supporting frame embodying the elements 7 and 9 may be readily adjusted vertically, and secured at the desired adjustment without disturbing the quilt. 80

Even though I have herein shown and described the preferred embodiment of the invention, it is to be understood that the same is susceptible of further changes, modifications and improvements coming within the scope of the appended claims. 85

Having thus described my invention, what I claim as new is:

1. A quilting frame comprising a pair of uprights each provided with a socket elongated longitudinally, and also having oppositely disposed slots providing lateral openings for said socket, an adjusting bar for each upright and slidably engaging the socket of said upright, means for securing each adjusting bar at the desired vertical adjustment to its upright, a frame member mounted on the upper end of each adjusting bar, rods bracing each frame member relative to its adjusting bar and operating in said 100

slots, and rollers rotatably mounted between said frame members.

2. A device of the character described, a work frame comprising end members respectively provided adjacent each end with a bayonet slot, rollers supported between said end members, sleeves on the ends of said rollers having reduced portions journaled in said slots, a ratchet wheel formed integral with the free end of each sleeve, pawls pivotally mounted on each end member and engaging said ratchet wheel, and vertically adjustable supporting means for said frame.

In testimony whereof I affix my signature.

15
